Patented Apr. 20, 1971

220,508

ALL-TERRAIN VEHICLE TOY

Thomas W. Good, Golden Valley, Minn., assignor to
Tonka Corporation, Mound, Minn.

Filed June 29, 1970, Ser. No. 23,696

Term of patent 7 years

Int. Cl. D21—02

U.S. Cl. D34—15

FIG. 2

FIG. 3

FIG. 4

FIG. 5

FIG. 1 is a top perspective view of an all-terrain vehicle toy showing my new design;

FIG. 2 is a top plan view thereof;

FIG. 3 is a side elevational view, the opposite side being a mirror image thereof;

FIG. 4 is a front elevational view thereof; and

FIG. 5 is a rear elevational view.

I claim:

The ornamental design for an all-terrain vehicle toy, as shown and described.
